UNITED STATES PATENT OFFICE.

BLAINE KITZMILLER, OF OAKLAND, CALIFORNIA.

MECHANICAL GAME DEVICE.

Application filed January 5, 1926. Serial No. 79,299.

This invention relates to mechanical devices intended to afford relaxation and amusement; and it consists in the novel construction, arrangement and combination of 5 parts, hereinafter described and later claimed.

The object of my invention is to provide an amusement device of the above type for the entertainment primarily of juveniles; it 10 is particularly suited as such for employment and enjoyment by groups of two or more persons. The game played on my device, being predicated upon the American game of baseball, will appeal more especially 15 to the youth of this country.

Briefly described, a ball inserted by the player in one of the openings on the playing face of my device, chosen by him at random, is delivered into such selected opening's corresponding receptacle, the ball during 20 its passage through the body of the device being entirely concealed from view. A name and a score point value is arbitrarily given each of the receptacles; and that 25 player who at the end of the game shall have scored the largest total of points wins the game.

In order that my invention may be clearly understood and readily carried into effect, 30 the same is hereinafter described with reference to the accompanying drawings, in which similar numerals indicate like parts. Of such drawings,

Fig. 1, is an elevation in cross section of 35 my device;

Fig. 2, is an end elevation of the primary tier;

Fig. 3, is a plan view, partly broken away, 40 of the primary tier;

Fig. 4, is an elevation of the secondary tier;

Fig. 5, is a cross section of Fig. 4, taken 45 on the line "X—X";

Fig. 6, is a plan view of the secondary tier;

Fig. 7, is a plan view of the apron;

Fig. 8, is an end view of the apron;

Fig. 9, is a plan view of the under side of 50 the movable plate;

Fig. 10, is an end view of said plate;

Fig. 11, is a side view of said plate;

Fig. 12, is a plan view of the cover 55 24;

Fig. 13, is an end view of said cover.

In detail, my construction is as follows:

55 Removably resting on inclined supports, 2, affixed to the sides of a housing, 3, is a pri-

mary tier of parallel decks, shown in the drawings to be seven in number, 4, 4^a, 4^b, 4^c, 4^d, 4^e, and 4^f; respectively,—deck 4 being the lowest of the tier. Binder posts, 5, tie the several decks together. Each deck is separated from its adjacent deck by spacer blocks, 6. On the upper projections of the four corner binder posts is placed a cover, 7, sometimes referred to herein as "the playing face," which covers said deck 4. This cover is provided with perforations, 8, of sufficient diameter to permit the passage of a ball, 9.

Carried by said deck 4^f, and projecting upwardly therefrom, are tubes, 10, less in 70 number than the number of perforations in said cover; these tubes terminate just short of contact with the under surface of said cover, and each tube is adapted to register with its corresponding perforation in 75 said cover. All tubes extend downwardly through said deck 4^f, some of them terminating flush with the under surface of the same; a lesser number continue on downward through deck 4^e and terminate flush with the under surface thereof; a still lesser number continue on downward through deck 4^d and terminate flush with the under surface thereof; a still lesser number continue on downward through deck 4^c and terminate flush with the under surface thereof; a still lesser number continue on downward through deck 4^b and terminate flush with the under surface thereof; and a still 80 lesser number continue on downward through deck 4^a and terminate flush with the under surface thereof. For clearness in the drawings, but one tube of each progressively decreasing in number series of tubes is shown. The arrangement of perforations is such that each tube will always register with a perforation no matter how the cover is inserted in the device.

Rigidly affixed to the sides of the housing, 3, is a secondary tier of seven parallel decks, 11, 11^a, 11^b, 11^c, 11^d, 11^e, 11^f, respectively,—deck 11 being the lowest of the tier. These decks are suitably tied together. Each deck is separated from its adjacent deck by spacer blocks 12, 12^a, 12^b, 12^c, 12^d, 12^e, 12^f, and 12^g,—block 12 being the lowest. The secondary tier constitutes a stop for the primary and prevents any downward movement of the latter when the primary is in position on the inclined supports, 2, above mentioned. The secondary tier, moreover, is so located with relation to the primary that it con-

stitutes a continuation of the primary along the same plane, and each deck thereof constitutes a continuation of each deck of the primary, is of the same thickness, and lies 5 in the same plane.

Each spacer block between its adjacent decks is suitably cut away to form V-shaped pockets, 13, 13^a, 13^b, 13^c, 13^d, 13^e, and 13^f.

At the apexes of these V's are circular passageways, 14, 14^a, 14^b, 14^c, 14^d, 14^e, and 14^f, which lead downward through the lowest deck of the tier; these passageways are of unequal length, are independent of each other, and do not intercommunicate.

15 To the bottom of the secondary tier, and on the same incline therewith, is secured an apron, 15. The apron is affixed to the sides of the housing, is supported in the rear by the pivoted braces, 16 and is supported in 20 the front by brackets, 17. On the upper surface of said apron I provide runways, 18, 18^a, 18^b, 18^c, 18^d, 18^e, and 18^f. Each runway is positioned directly below the opening in the passageway which it is to serve, i. e., runway 25 18^f is immediately below passageway 14^f; runway 18 is immediately below passageway 14, etc. Each runway inclines downwardly, pursues a different course, and leads to a receptacle peculiar to itself. That 30 is, runway 18^f leads to receptacle marked "Out—no score"; runway 18^e to receptacle marked "Base on balls—1 point"; runway 18^c to receptacle marked "Sacrifice hit—2 points"; runway 18^e to receptacle marked "1 35 Base hit—3 points"; runway 18^b to receptacle marked "2 Base hit—4 points"; runway 18^a to receptacle marked "3 Base hit—5 points"; and runway 18 to receptacle marked "Home run—6 points." Each of these receptacles is provided with an opening, 19.

On the under surface of said apron I mount a movable plate, 20, provided with openings, 21, adapted to register with said openings, 19, in said receptacles when said 45 plate is operated. By means of a pivoted lever, 22, said plate may be moved against the action of the spring, 23, which otherwise holds said plate in such position that said openings 19 and 21 do not coincide. When 50 said openings are out of alignment said plate constitutes the bottom of said receptacles. By means of a cover, 24, the lower end of the secondary tier and the runways leading to the several receptacles are hidden from 55 view. When the lever is operated the played balls drop through the openings 21 into a receiver, 25.

My device is operated as follows: The cover is placed in position over the primary 60 tier and the housing is closed. The device is then in condition to be played. Players are provided with a number of steel balls, and one from among them chosen to begin the play. The player then inserts one of 65 the balls in one of the perforations on the

playing face; he must make his choice at random as there is nothing visible to guide him in making his selection.

If the perforation into which the player inserts the ball does not register with any 70 of the tubes, 10, the ball in falling will strike deck 4^f; it will then roll downward across said deck into V-shaped pocket 13^f; then through passageway 14^f; then into runway 18^f; and then be led into receptacle 75 marked "Out,"—whereupon the player will be entitled to score no points. But if the perforation chosen by the player registers with one of the tubes, then the ball in falling will strike the next deck below such tube, 80 and the ball will roll downward across such deck, into the V-shaped pocket, drop through the passageway, into the runway, and be led into such deck's corresponding receptacle; and the player will then be entitled 85 to score the points ascribed to the receptacle affected. For example, if the tube effected ends above deck 4 the ball rolls downward across deck 4 into pocket 13, through passageway 14, into runway 18, and is led into receptacle marked "Home run," whereupon the player scores 6 points. The above illustrations should suffice, as the course of the ball and the receptacle into which it falls in other instances will be apparent from the 90 drawings. Obviously more "outs" than "points" will be made as almost all the perforations have no tubes immediately beneath them and communicate directly with deck 4^f. After scoring his points, the player drops the 100 played ball into the receiver, 25, by operating the lever, 22. The winner is the player whose score is highest at the end of the play.

No part of my device is open to the view of the players except the playing face and 105 the several receptacles, and the ball is hidden from view during its entire passage through the body of my device.

I would have it understood that the construction herein illustrated and particularly 110 described is intended to exemplify what is at present regarded to be the preferred embodiment of my invention, and that the invention may be otherwise and variously embodied without departing from its spirit or 115 the scope of the subjoined claims.

Having thus described my invention, what I desire to claim and to secure by Letters Patent is:—

1. In a game device in which the scoring 120 of points is dictated by chance, a housing, a removable tier of inclined decks, a cover, perforations for said cover adapted to receive a spherical body, non-intercommunicating conduits between said decks and said 125 cover, a secondary tier of inclined decks, V-shaped pockets for said secondary tier, passageways at the apexes of said pockets, runways below said passageways, and receptacles at the lower ends of said runways. 130

2. In a game device in which the scoring of points is dictated by chance, a housing, a removable tier of inclined decks, a cover, perforations for said cover adapted to receive a spherical body, non-intercommunicating conduits between said decks and said cover, a secondary tier of inclined decks, V-shaped pockets for said secondary tier, passageways at the apexes of said pockets, runways below said passageways, receptacles at the lower ends of said runways, a movable bottom for said receptacles, and means for emptying said receptacles when filled.

3. In a game device, a tier of inclined decks, a cover for said tier, perforations for said cover, conduits between each deck and said cover, a receptacle for each deck, independent means of communication between

the several decks and their corresponding receptacles, the whole comprising means whereby a spherical body dropped through one of said perforations is delivered to its corresponding receptacle.

4. In a game device in which the scoring of points is dictated by chance, a housing, a tier of parallel inclined decks, a cover, perforations for said cover, non-intercommunicating conduits between the several decks and said cover, a receptacle adapted to receive a spherical body for each deck, and non-intercommunicating passageways connecting said decks and their respective receptacles.

In testimony whereof I have hereunto affixed my signature.

BLAINE KITZMILLER.
